UNITED STATES PATENT OFFICE.

JOSEPH P. LAVIGNE, OF DETROIT, MICHIGAN, AND DANIEL J. MURNANE, JR., OF CHICAGO, ILLINOIS.

FASTENING DEVICE.

1,402,775.

Specification of Letters Patent. Patented Jan. 10, 1922.

Application filed November 10, 1919. Serial No. 336,883.

To all whom it may concern:

Be it known that JOSEPH P. LAVIGNE and DANIEL J. MURNANE, Jr., citizens of the United States of America, residing at Detroit, in the county of Wayne and State of Michigan, and Chicago, county of Cook, Illinois, respectively, have invented certain new and useful Improvements in Fastening Devices, of which the following is a specification, reference being had therein to the accompanying drawings.

Glaziers when mounting plate glass in window frames, show cases and other structures are instructed to leave a defined space between confronting edges of glass plates and not tighten the fastening means of the glass plate too much, but instead of obeying such instructions it will be found that glass plates are mounted so that they are broken, either due to expansion or too great a pressure on the plate by the fastening means thereof. Some times a glazier will use a wrench, pair of pliers or other tools to operate the fastening means of the glass plate and when such spring pressure is brought to bear on the edges of the plate the glass is invariably blemished, cracked, chipped or sometimes the entire plate broken. When not leaving sufficient space at the confronting edges of two plates for expansion of either, one or both of the plates may be injured, as mentioned above, so to prevent such negligence on the part of the glazier we have devised plate glass holding means which will assure the proper amount of space between the confronting edges of the glass plates and at the same time prevent the glazier from bringing excessive pressure to bear when clamping or mounting the plates in the frame between the clamping rails.

Our invention further aims to provide a plate glass fastening device which cannot be installed except by providing the defined space between the confronting edges of the glass plates, and after the fastening device has been installed it is practically impossible to adjust the fastening device except with the fingers and consequently too great a pressure, as by leverage, cannot be brought to bear on the fastening device.

Our invention further aims to provide a glass plate fastener that may be used at the edge of a glass plate whether the same is in alinement with another plate, at an

angle thereto or at a rail or other support, consequently we do not care to confine our invention to any particular window or show case construction, other than as defined by the appended claims.

Our invention will be hereinafter more fully considered and reference will now be had to the drawings, wherein—

Fig. 1 is a side elevation of a fastening device in connection with the two plates of glass;

Fig. 2 is a rear elevation of the same;

Fig. 3 is a horizontal sectional view of the fastening device;

Fig. 4 is a similar view of the fastening device in connection with two plates of glass disposed at an angle to each other;

Fig. 5 is a side elevation of another form of fastening device in connection with a single plate of glass;

Fig. 6 is a cross sectional view of the same;

Fig. 7 is a horizontal sectional view taken on the line VII—VII of Fig. 6;

Fig. 8 is a cross sectional view of a modified form of fastener, and

Fig. 9 is a horizontal sectional view taken on the line IX—IX of Fig. 8.

Reference will first be had to Figs. 1, 2 and 3 showing the fastening device as holding the confronting edges of two alining glass plates 1 between an inner frame or rail 2 and an outer frame or rail 3. The inner frame 2 is hollow and more or less ornamental with two inwardly projecting longitudinal flanges 4 against which glass plates 1 are placed with or without gaskets or cushion members therebetween.

The outer rail or frame 3 is somewhat in the form of a channel bar providing opposed longitudinal guides 5 and a central longitudinal raised portion 6 which takes the form of a bead on the outer frame.

Mounted in the guides 5 of the outer frame 3 is a longitudinal plate 7 and centrally of said plate is a tension member or tie rod 8 having a head 9 in the raised portion or bead 6 of the outer frame 3. The plate 7 serves as a large head on the end of the tie rod 8 and permits of said tie rod being shifted in the outer frame to a desired position. The tie rod 8 is adapted to be inserted between the glass plates 1 and into the inner frame or rail 2 so that the guides 5 of the outer frame will co-

operate with the flanges 4 of the inner frame in clamping and holding confronting edges of the glass plates 1. A gasket or suitable cushion member may be interposed 5 between the glass plate and the outer frame. Before the tie rod 8 can be inserted between the glass plate 1, it is necessary that said plates have the confronting edges thereof properly spaced apart so as to provide 10 clearance for a cup shaped spacing member 10 fixed on the tie rod 8. The spacing member 10 is in spaced relation to the plate 7 and this arrangement necessitates moving the spacing member 10 from 15 between confronting edges of the glass plates before the outer frame 3 can be brought into engagement with the glass plates. Consequently there is no danger of the spacing member 10 being left between 20 the confronting edges of the glass plates. The tie rod 8 has a threaded end 11 extending out of the wall 12 of the inner frame 2 and provided with a knurled nut 13, which is held against the wall 12 by a housing 25 or strap 14 pivoted or otherwise connected, as at 15, to the wall 12. The housing or strap 14 has its side edges cut away, as at 16, so as to expose the periphery of the nut 13 and permit of the fingers readily gripping 30 the same to rotate the nut and shift the tie rod 8. The housing or strap 14 prohibits the use of a wrench, pair of pliers or other tool for rotating the nut, consequently excessive pressure cannot be brought 35 to bear by the tie rod 8 which would cause the inner and outer rails to crack or otherwise injure the glass plates 1 clamped between said frames.

As shown in Figs. 1 and 2 the fastening 40 devices can be suitably spaced throughout the inner and outer frames so that the confronting edges of the glass plates will be positively held between said frames.

The principle thus far involved may be 45 embodied in corner frames 17 and 18 shaped for engagement with the edges of glass plates 19 placed at an angle relative to each other, and outside of the frames 17 and 18 being shaped to engage the glass plates the 50 fastening device is identical with that previously described.

The fastening device for the edge of a single glass plate 20 is shown in Figs. 5, 6 and 7, the glass plate being engaged by an 55 inner frame or rail 21 and an outer frame or rail 22, both of which may have a desired cross-sectional shape or be more or less ornamental and similar to molding. The outer frame or rail 22 affords guides 23 for a plate or head 24 carried by a tie plate 25 which extends into a journal member 26 fixed in the inner frame 21. The tie plate 25 has an opening or slot 27 providing clearance 60 for a cam or an eccentric 28 on a stem 29 journaled in the member 26. The upper

end of the stem, within the frame 21, has a knurled nut 30 with a portion of its periphery protruding from a slot 31 in the frame 21, so that the nut may be gripped with the fingers to rotate the stem 29 and turn the cam or eccentric 28 in the opening or slot 27. The turning of the cam or eccentric 28 shifts the plate 25 and moves the outer frame or rail 22 relative to the glass plate 20, whereby it is possible to clamp the glass plate between the inner and outer frames. This is accomplished without any danger of excessive pressure being brought to bear upon the edge of the glass plate by either 75 of the frames or rails.

A modification of the fastener is shown in Figs. 8 and 9, wherein the journal member 26 has stamped out portions 32 providing a guide for the end of the tie plate 25, which is provided with an angular flange 33 engaging the journal member 26. In the journal member is a screw 34 having a knurled nut 35 disposed similar to the nut 30 and on the screw 34 is a wedge nut 36 non-rotatably held by the tie plate 25 and adapted to be raised and lowered against the flange 33 of said tie plate to move the outer frame 22 relative to the inner frame 21. The tie plate 25 has an opening providing clearance for the wedge nut 36, as best shown in Fig. 9 and this form of fastener, as well as that shown in Figs. 5, 6 and 7 permits of lateral pressure being brought to bear on the tie plate to properly clamp the edge of the glass plate 20 between said frames.

What we claim is:

1. A glass plate fastener comprising inner and outer frames, tension means engaging one of the frames and extending to the other for moving one frame with relation to the other, a rotatable fastening means engaging the tension means and the other frame and a housing partially enclosing the rotatable fastening means to permit its rotation by the fingers but to prevent effective engagement therewith of a grasping tool.

2. In a glass plate fastener, frames, and adjustable means for clamping said frames against the glass plate said adjustable means having a portion thereof enclosed and a portion exposed whereby movement of the adjustable means may be accomplished by grasping it with the fingers, but the enclosed portion being inaccessible to a grasping tool so as to prevent excessive adjustment.

3. The combination with a glass plate, of a frame, clamping means for said glass plate on said frame and means for adjusting said clamping means having a portion enclosed and a portion accessible to the fingers of the operator whereby adjustment of the clamping means may be made by the fingers while the presence of the enclosure renders the use of a grasping tool difficult.

4. The combination with glass plates, of inner and outer frames engaging the ad-

5 jacent edges of the plates, a tension member having one end secured to one of the frames and extending between the edges of the plates and the other end adapted to receive means whereby it is secured to the other frame and a spacing member secured upon the tension member at a distance from its point of attachment to their first named frame greater than the 10 thickness of the glass plates, whereby in assembling the frames upon the plates, sufficient space must exist between the adjacent edges of the plates to permit the passage of the spacing means, but when the frame lies 15 in contact with the plates, the spacing member lies at one side of the plane of the plates.

5. The combination with glass plates having the edges thereof spaced apart, of means 20 insertable between the edges of the plates to hold the plates in clamped position, said means having thereon a spacing member of such dimensions that when the clamping means is inserted, the plates must be at least a predetermined distance apart to permit the

25 passage of the spacing member, and the said spacing member being so located upon the clamping means that when the parts are assembled the spacing member does not lie in the plane of either plate.

6. The combination with glass plates having edges thereof spaced apart, of an outer frame, a tie rod having one end rigidly secured to the outer frame and having thereon a spacing member spaced from the outer frame a distance greater than the thickness 35 of the glass plates, and an inner frame through which the tie rod extends, and means engaging the tie rod and the inner frame, adapted to exert longitudinal tension upon the tie rod to clamp the frames in position 40 on the glass plates.

In testimony whereof we affix our signatures in presence of two witnesses.

JOSEPH P. LAVIGNE.
